UNITED STATES PATENT OFFICE

147,705

DESIGN FOR A HOUSE PLAN TEMPLATE

Guyles B. Wiley, also known as Guy Wiley,
Columbus, Ohio

Application December 26, 1945, Serial No. 125,032

Term of patent 14 years

(Cl. D52—1)

To all whom it may concern:

Be it known, that Guyles B. Wiley, also known as Guy Wiley, a citizen of the United States, residing at Columbus, in the county of Franklin and State of Ohio, has invented a new, original, ornamental Design for a House Plan Template, of which the following is a specification, reference being had to the accompanying drawing, forming part thereof, wherein:

I claim:

The ornamental design for a house plan template, as shown.

GUYLES B. WILEY,
Also Known as Guy Wiley.
